PNEUMATIC HORN OR SIGNAL

Lawrence Abbondandolo, Brooklyn, N. Y.

Application March 12, 1949, Serial No. 81,055

14 Claims. (Cl. 116—139)

1

This invention relates to audible signals generally and more particularly to pneumatic signals for use on bicycles, tricycles, boats, wagons and other types of vehicles regardless of their size or purpose.

The present invention proposes a pneumatic signal or horn wherein delicate and readily breakable parts, or parts subject to deterioration, are eliminated to produce a sturdy, long lasting device, simple in construction and not easily susceptible to damage, breakage or material deterioration.

Among its other objects the present signal or horn contemplates a device that will have a small overall size and yet will pneumatically produce a uniform, loud and distinctive signal by the discharge of a comparatively large volume of air under positive pressure through an associated sound producing assembly.

Moreover, the instant invention by the inclusion of a resonating chamber increases the magnitude of the sound or signal produced without increasing proportionately the volume of air under pressure, as would customarily be required for a signal of equal magnitude by other devices of this character.

By the simplicity of its construction, the durability and rigidity of its components, and the elimination of fragile or easily broken parts, such for example as reeds, and the substitution of a rigid, non-flexible air compressor for the elastic bulb or diaphragm heretofore common in pneumatic signals or horns, the present invention produces a pneumatic signalling device relatively inexpensive to construct and assemble, and yet practically indestructible.

With the above and other objects in view, as will be apparent, this invention consists in the construction, combination and arrangement of parts all as hereinafter more fully described, claimed and illustrated in the accompanying drawings wherein:

Fig. 1 is a side elevation of a pneumatic signal or horn constructed in accordance with the present invention and illustrates in phantom lines one type of mounting means by which it may be secured in an operative position;

Fig. 2 is a central longitudinal section through the horn taken along line 2—2 of Fig. 1;

Fig. 3 is a transverse section taken along line 3—3 of Fig. 1;

Fig. 4 is a central longitudinal section through a modified form of the instant horn or signal illustrating the relative positions of the components thereof prior to operation;

2

Fig. 5 is a view similar to Fig. 4 illustrating the relative positions of the components of the presnet horn or signal after its operation and the completion of the signal;

5 Fig. 6 is a transverse section taken along lines 6—6 of Fig. 4, and

Fig. 7 is a fragmentary elevation of Fig. 4 to show the manner in which the air compressor element and the resonating tube are operatively connected.

10 Heretofore pneumatic horns or signals, regardless of their purpose, have usually employed an open bell in association with reeds or diaphragms to be vibrated or flexed by air pressure produced by the repeated compression of an elastic bulb or similar device, each compression of the bulb passing a limited quantity of compressed air through or over the reed or diaphragm. This type of pneumatic horn or signal has been comparatively expensive and difficult to maintain because of the rapid deterioration of the bulb, with or without use, and the frequent breaking of the reed or diaphragm.

15 The present invention proposes an assembly to produce a loud, but pleasant and distinctive signal without the use of a reed, diaphragm or other vibrating member and without employing the bulb heretofore used as a source of air under pressure.

20 Reference being had more particularly to the drawings, 10 designates the main cylinder or barrel of the present invention, which is of rigid construction and made of any suitable material such as metal, synthetic resins or the like. At one of its ends the cylinder 10 is open while at its opposite extremity it is provided with an end wall 11 in which is created a central aperture, concentric to the axis of the cylinder 10. This aperture is surrounded by an outstanding flange 12 formed integrally with the end wall 11. Within the flange is positioned a hollow collar 13 resting flush against the inner surface of the flange 12 where it is fixedly secured by any suitable means, such as the screw 14 passing through the flange 12 and imbedded in or engaging the collar 13.

25 At its inner end the collar 13 terminates in the plane of that portion of the end wall 11 immediately adjacent the flange 12 and abuts a bearing plate 15 situated within the cylinder 10 and resting flush against the inner face of the wall 11. This bearing plate 15 is permanently secured to the wall 11 in any manner and to that end may be welded to the inner face of said wall in close abutment with the inner end of the collar 13. A bearing opening 15' centrally pierces

the plate 15 concentrically to the collar 13 and this opening is surrounded by a plurality of air passages or apertures 16 each of which communicates at one end with the interior of the cylinder 10 and at its opposite end with the interior of the collar 13.

The outer end of the collar 13 projects beyond the edge of the flange 12 and there surrounds and contains a disc 17 which constitutes an air baffle or constriction in said collar. This disc 17 is positioned concentric to the axis of both the cylinder 10 and collar 13 and is held circumferentially spaced from the interior surface of the collar whereby a narrow space 18 is created between the periphery of the disc and the end portion of the collar 13. The position of the disc 17 is maintained and held in its spaced relation to the collar 13 by pins 19 which after piercing the collar are imbedded at their inner ends in the edge of said disc. It is obvious that the disc 17 need not be mounted and held in place by the pins 19 but may be secured in its operative position within the outer extremity of the collar 13 by any other suitable means and may even be made integrally with the collar in which event the space 18 may be routed out leaving integral necks corresponding to the pins 19 as the means for support interposed between the disc 17 and collar 13.

Mounted for reciprocation within the open end 30 of the cylinder 10 is an air compressor. This compressor comprises a body 20 of any suitable shape, here shown as semi-elliptical in longitudinal section and circular in cross-section, having an inner end wall 21. A flexible packing member, 35 preferably of leather 22, is mounted against the outer face of the end wall 21 of the compressor with its edge portion protruding beyond the limits of said wall to produce a peripheral flange 23 disposed angularly to said end wall 21 and operable against the inner surface of the cylinder 10. This packing member 22 is held in place flush against the end wall 21 of the compressor by a clamping plate 24 disposed over the packing member and substantially coextensive with the wall 21. A piston rod 25 at one of its ends is concentrically threaded, as at 26, into the end wall 21 of the compressor 20. A lock nut 27 is mounted on the threaded portion 26 of the rod 25 to bear against the exposed face of the clamping plate 24 and thereby serves to rigidly lock the clamping plate 24 and the packing member 22 in their operative positions in association with the end wall 21 of the compressor and to counteract any tendency to retrograde rotation by the rod 25. In practice the body 20 of the compressor acts as the means by which it is reciprocated inwardly of the cylinder 10 while the end wall 21, the packing member 22 and the clamping plate 24, in their operative association, combine to comprise a piston reciprocable within said cylinder.

The piston rod 25 is positioned to coincide with the longitudinal axis of the cylinder 10 and therefore passes through the bearing opening 15' in the plate 15 and projects into the collar 13. In alignment with the opening 15' of the plate 15 the disc or baffle 17 is provided with a central bearing opening 17' through which the outer end portion of the rod 25 projects and reciprocates. Exteriorly of the disc 17 the rod 25 is associated with a washer 28 which is held fixed in its position at the extremity by a screw 29 threaded into the outer extremity of the rod. This washer, as will be seen, acts as a stop to limit the movement of the rod 25 and of the compressor and

associated parts in one direction, i. e., outwardly of the open end of the cylinder 10.

Within the cylinder 10 and interposed between the end wall 21 thereof and the clamping plate 24 of the piston of the compressor is a helical spring 30. If and when the compressor 20 is moved inwardly of the cylinder 10 the substantially airtight contact between the packing member 22 and the piston 21-22-24 at the inner end of the body 20 compresses the air within the cylinder 10 between said piston and the end wall 21 of the cylinder. The air thus compressed by the compressor 20 is expelled from the cylinder 10 through the air passages or apertures 16 in the bearing plate 15 into the collar 13, from which it escapes or is expelled through the space 18 between the disc 17 and the inner surface of the collar 13. The compression of the air and its ultimate expulsion through the space 18, generates a comparatively loud, audible signal which is amplified by the provision of a resonating chamber in association with the outer end of the collar 13, as will be more fully described.

When the compressor has reached the limit of its stroke inwardly of the cylinder 10, the spring 30 is fully compressed and therefore will return the compressor to its original position (Fig. 2) when it is released or freed. The movement of the compressor 20 outwardly of the cylinder 10 is arrested when the washer 28 contacts the outer surface of the disc 17.

A resonating chamber 31 is provided in conjunction with the outer extremity of the collar 13. This chamber consists of a cylindrical tube 32 having the same diameter as the collar 13 and flared at its outer end 33 as at 34. A closure 34 is provided for the outer extremity of the flare 33 whereby the flare or bell 33 is sealed and the discharge of air under pressure into the chamber 31 develops a back pressure which increases the magnitude of the sound produced at disc 17. The tube 32 and the flared portion 33 can be formed integrally with the closure 34 or the latter may be welded or otherwise permanently secured to the extremity of the flare 33 to effectively close and seal that end of the chamber 31.

At its inner end the tube 32 of the resonating chamber is spaced from and mounted on or secured to the outer extremity of the collar 13 by the attaching members 35 interposed between the outer extremity of the collar 13 and the inner extremity of the tube 32. These attaching members are relatively narrow, rigid extensions of the collar 13 and the inner edge of the tube 32. Any one of many techniques may be employed to rigidly and permanently mount the tube 32 on the outer extremity of the collar 13 by the interposed attaching members 35. For example the attaching members may be formed integrally with both the tube 32 and the collar 13 or they may be formed separately and welded at their ends to both the collar and the tube. If formed integrally with the tube 32 and the collar 13, the space between the inner end of the tube 32 and the outer end of the collar 13, which is traversed by the attaching members 35, may be created by partly routing out or partially cutting a single tube to define the inner end of the tube 32 and the outer end of the collar 13 and produce the space between them. In doing this the attaching members 35 are allowed to remain integral with both the tube 32 and the collar 13 and to traverse the space thus formed. The method by which the attaching members are formed or are inserted between the adjoining ends of the tube

32 and the collar 13 is a matter of manufacturing expediency and per se forms no part of the present invention which merely requires that the inner end of the tube 32 be separated from the outer end of the collar 13 and that they be permanently and rigidly held in such relationship.

When the compressor is moved inwardly of the cylinder 10 the air compressed thereby is expelled through the space 18 between the disc 17 and the collar 13 thus generating an audible signal the volume and magnitude of which is increased by the resonating chamber 31 aligned with the collar 13 but spaced therefrom.

The pneumatic horn or signal above described may be associated with a vehicle in any suitable manner and it is not proposed to limit the scope of the present invention by including therein any specific mounting means. An example of one means by which the present device may be mounted is disclosed in dotted lines in Fig. 1. Here a ball 36 is rigidly fixed to the cylinder 10 to be releasably clamped between the jaws 36' of the adjustable support. These jaws 36' are disposed at corresponding ends of the clamping members 37 which are provided medially of their lengths with the complementary outwardly curved, engaging portions 38 designed to partially surround and clampingly engage between them a part of the vehicle, as for instance, the handlebar of the bicycle. Above the engaging portions 38 of the clamping members 37, a set screw 39 is provided to adjust the engaging pressure of the jaws 36' on the ball 36 and the outer extremities of the clamping members 37 are also traversed by a similar set screw 40 whereby the pressure of the engaging portions 38 of the clamping members 37 on a part of the vehicle may be regulated.

In Figs. 4, 5, and 6 is illustrated a modified form of the present invention by which a two-tone signal is produced. In this form of the invention the compressor 20 and the cylinder 10 are formed substantially as shown in Figs. 1, 2, and 3 and this is also substantially true of the resonating chamber 31. The salient differences between the structure of this modified form of the invention and structure of the form shown in Fig. 2 resides in the components associated with the flange 12 of the cylinder 10 and those parts associated with the inner extremity of the tube 32 of the resonating chamber 31.

In Figs. 4 and 5 the tube 32 of the resonating chamber 31 extends into and rests flush against the inner surface of the flange 12 where it is removably held by pins 41 fixedly secured to the tube engaging in bayonet slots 42 formed in the flange 12. The inner extremity of the tube 32 abuts the bearing plate 15 just as in Fig. 1. Outwardly of the collar 12 the tube 32 of the resonating chamber 31 is provided with a pair of parallel openings 43 and 44 spaced longitudinally of the tube one from the other. These openings are each the equivalent of the space between the inner extremity of the tube 32 and the outer extremity of the collar 13 in Fig. 1 and each functions in the same way, means being provided to close one opening when the companion opening is opened so that never more than one of them is operative.

The primary opening or space 43 is thus closed when the secondary opening 44 is open and vice versa. To accomplish and control this alternate effectiveness of the spaces or openings 43 and 44 the inner extremity of the tube 32 is provided with a reciprocable sleeve 45 having a single space or opening 46 formed circumferentially therein centrally of its length. The sections of

the sleeve 45 defining the opening or space 46 are traversed by a series of connectors 47 which are permanently secured at their ends to said sections of the sleeve in any suitable manner. These connectors may be formed integrally with the sections of the sleeve 45, or may be created separately and welded or otherwise secured to these sections at their ends. Any suitable manufacturing technique may be employed in producing the sleeve 45 so long as two cylindrical sections of sleeve are created, spaced one from the other and rigidly and permanently connected one to the other to constitute a single unitary mechanism. Within the inner section 45' of the sleeve is mounted a disc 17^a, which is a replica, as to relative size, structure and mounting of the disc 17 (Fig. 2). This disc 17^a is permanently and rigidly mounted in the inner section 45' of the sleeve at one side of the space or opening 46 between the sleeve sections. As in the case of the disc 17 (Fig. 2) the disc 17^a is spaced circumferentially from the interior surface of the section 45' of the sleeve. Fixed concentrically to the inner surface of the disc 17^a in any suitable manner is a hollow rod 48 designed to reciprocate within the central opening of the bearing plate 15 secured to the inner face of the end wall 11 of the cylinder 10, as the sleeve is moved to occupy either of its two operative positions with respect to the tube 32.

The piston rod 25 extends concentrically through the hollow rod 48 and at one end is secured to the piston 21-22-24 of the compressor as disclosed in Fig. 2 and described in conjunction therewith. The spring 30, disposed between the piston of the compressor 20 and the inner face of the end wall 11 of the cylinder 10, functions exactly as the spring 30 in Fig. 2. Thus when the compressor is moved inwardly of the cylinder 10 it compresses the spring 30 between its piston 21-22-24 and the end wall 11 of the cylinder and moves the piston rod 25 longitudinally within the hollow rod 48. At that moment the space or opening 46 between the sections 45 and 45' of the sleeve is aligned or registered with the primary or inner space or opening 43 in the tube 32 of the resonating chamber 31. The air compressed within the cylinder 10 and expelled by the piston of the compressor will be ejected through the air passages 16 of the supporting plate 15 into the inner section 45' of the sleeve to escape around the disc 17^a and out through the primary space or opening 43 in the tube 32.

A small compression spring 49 surrounds the piston rod 25 adjacent the lock nut 27 and as the piston 21-22-24 of the compressor moves inwardly of the cylinder 10 this spring will eventually contact the inner end of the hollow rod 48, whereupon the continued movement of the compressor will move the hollow rod 48 within the supporting plate 15 and the tube 32 of the resonating chamber 31. This movement of the hollow rod 48, carrying with it the sleeve 45-45' and the disc 17^a, will cause the section 45' of the sleeve to close the primary opening 43 in the tube 32 of the resonating chamber 31 and will simultaneously move the section 45 of the sleeve to open the secondary opening 44 of said tube. When this adjustment of the sleeve is completed the air compressed by the compressor will be expelled through the openings 16 of the bearing plate 15 and the inner end of the tube 32 of the resonating chamber 31 and be delivered to and through the inner section 45' of the sleeve for ultimate discharge outwardly through the space

around the disc 17^a and the secondary opening 44 in the tube 32 of the resonating chamber.

The movement of the sleeve 45—45' is arrested by stops 59 properly situated in and secured to the interior of the tube 32. When the movement of the compressor 20 inwardly of the cylinder 10 is arrested and is then released, the spring 30 will move the compressor to its original position shown in Fig. 4. During the initial part of this return movement the piston rod 25, under the impetus of the spring 30, will move within and independently of the hollow rod 48 from the position shown in Fig. 5 until the washer 28 contacts with the outer surface of the disc 17^a whereupon the rod 25 and the hollow rod 48 together with the sleeve 45—45' will move in unison until the inner end section 45' of the sleeve contacts the bearing plate 15.

The two extreme positions of the modified form of the present invention are shown in Figs. 4 and 5. In Fig. 4 the compressor 20 is situated by the spring 30 at the outer limit of its path of movement with the washer 28 or other suitable head of the piston rod 25 bearing against the outer surface of the disc 17^a. With the compressor in this position the outer section 45 of the sleeve closes the secondary opening 44 in the tube 32 and the opening or space 46 between the sections 45 and 45' of the sleeve is in alignment or registration with the primary opening 43 of the tube 32.

In Fig. 5 the parts are shown in the positions they respectively occupy when the compressor is at the inner limit of its path of movement. Here the springs 30 and 49 are shown fully compressed and the sleeve 45—45' has been moved by the hollow rod 48, due to its contact with the inner spring 49, to a position where the inner section 45' of the sleeve seals the primary opening 43 of the tube 32 and the outer section 45 of the sleeve has been moved to clear or open the secondary opening 44 of the tube.

The release of the compressor 20 will permit the spring 30 to operate to move the compressor outwardly of the cylinder 10, in which event the rod 25 moves with the compressor until its head or washer 28 contacts the outer end of the hollow rod 48 and the disc 17^a whereupon the sleeve 45—45' and the hollow rod 48 together with the disc 17^a will move in unison with the rod 25 and until the parts have reassumed the position shown in Fig. 1.

It will be observed that all of the components of the present signal or horn, with the exception of the packing member or seal 22, are solid and rigid in construction and that no flexible or fragile parts or elements are used. Thus the repeated operation of the device causes no deterioration of its parts and so long as an airtight connection is maintained between the piston 21—22—24 of the compressor 20 and the inner surface of the cylinder 10 there will be no leakage or any deterioration whatever of the assembly or any of its parts.

What is claimed is:

1. The combination with a hollow cylinder, having one of its ends open and a centrally apertured end wall at its opposite end, of an outwardly projecting flange fixed to the outer face of the end wall of the cylinder to define and surround the central aperture therein, a bearing plate permanently secured to the inner face of said end wall provided with a central aperture registering with the aperture of the end wall and with a plurality of air passages disposed radially

about said aperture, each passage at its opposed ends communicating with the space defined by said flange and with said cylinder, a compressor mounted for reciprocation in the open end of said cylinder embodying a piston having sealing contact with the inner surface of the cylinder, a piston rod affixed centrally to the piston of the compressor and extending through the central aperture of the bearing plate, a compression spring interposed between the end wall of the cylinder and the piston of the compressor to normally move the latter in a direction outwardly of the cylinder and away from said end wall, a tube fixed to and projecting outwardly from the flange on the end wall of the cylinder pierced by an opening in its wall near said flange and having its opposite end portion flared outwardly, a permanent closure sealing the extremity of the flared end portion of the tube, a disc mounted in the tube adjacent the opening in the wall thereof, with its periphery spaced from the surrounding structure, said disc having a central aperture in axial alignment with the apertures in the end wall of the cylinder and in the bearing plate for the reception and passage of the piston rod of the compressor, and means on the extremity of said piston rod externally of the disc to limit the movement of said rod and attached compressor outwardly of the open end of the cylinder under the influence of the aforesaid spring.

2. The combination with a hollow cylinder open at one of its ends and having a generally apertured end wall at its opposite end, of an outwardly projecting flange fixed to the end wall of the cylinder to surround the central aperture therein, a bearing plate permanently secured to the inner face of said end wall in opposition to said flange and having a central opening therein concentric to the aperture in the end wall and a plurality of air passages disposed around said opening, each air passage communicating at one end with the space defined by said flange and at its opposite end with the interior of said cylinder, a compressor mounted for reciprocation in the open end of said cylinder comprising a body having the major part thereof normally projecting from the open end of the cylinder, an end wall always positioned within the cylinder, a packing member resting flush against said end wall with its edge projecting beyond the limits thereof for sealing contact with the inner surface of the cylinder, and a clamping plate overlying the packing member and securing it in its operative position, said packing member and clamping plate in association with the end wall of the compressor constituting the piston of the compressor, a piston rod affixed centrally to the piston of the compressor and extending through the central opening of the bearing plate, a compression spring interposed between the end wall of the cylinder and the piston of the compressor to normally move the latter in a direction outwardly of the cylinder, a tube fixed within and projecting outwardly from the space defined by the flange on the end wall of the cylinder, having an opening in its wall adjoining the edge of said flange and its outer end portion flared, a permanent closure sealing the extremity of the flared end portion of the tube, a disc mounted in the tube adjacent the opening in the wall thereof with its periphery spaced from the inner surface of the tube, said disc being provided with a central opening in axial alignment with the openings in the end wall of the cylinder and in the bearing plate for the reception and passage of

the piston rod of the compressor, and means on the extremity of the piston rod externally of the disc to limit the movement of said rod and attached compressor outwardly of the open end of the cylinder, under the influence of the aforesaid spring, by contact thereby with the outer face of said disc.

3. The combination with a cylinder having one of its ends open and a centrally apertured end wall at its opposite end, of an outwardly projecting flange fixed to the end wall of the cylinder to surround and define the central aperture therein, a bearing plate permanently secured to the inner face of said end wall in opposition to said flange and provided with a central opening therein concentric to the aperture of the end wall and a plurality of air passages disposed about said opening, each air passage terminating at one end in communication with the space defined by the flange and at the opposite end with the interior of the cylinder, a compressor mounted for reciprocation in the open end of said cylinder comprising a body, the major part of which normally projects from the open end of the cylinder, an end wall attached to said body to be always located within the cylinder, a packing member resting flush against said end wall of the compressor with its edge projecting beyond the limits thereof for sealing contact with the inner surface of the cylinder, and a clamping plate overlying the packing member and securing it in its operative position, said wall, packing member and clamping plate in association constituting the piston of the compressor, a piston rod affixed centrally to the piston of the compressor and extending through the central openings of the bearing plate and end wall of the cylinder, a compression spring interposed between the end wall of the cylinder and the piston of the compressor to normally move the latter in a direction outwardly of the cylinder, a tube fixed within and projecting outwardly from the space defined by the flange on the end wall of the cylinder, having its outer end portion flared and several openings in its wall adjoining the edge of said end wall flange, each such opening being defined by relatively narrow connectors interposed between that part of the tube situated within said flange and the edge of the tube opposed thereto, a permanent closure sealing the extremity of the flared outer end portion of the tube, a disc supported in the tube adjacent the openings therein with its periphery spaced from the inner surface of the tube, said disc having a central opening in axial alignment with the openings in the end wall of the cylinder and in the bearing plate for the reception and passage of the piston rod of the compressor, and means on the extremity of the piston rod externally of the disc to limit the movement of said rod and of the attached compressor outwardly of the open end of the cylinder under the influence of the aforesaid spring by contact thereby with the outer face of said disc.

4. The combination with a cylinder having one of its ends open and its opposite end closed by a centrally apertured end wall, of an outwardly projecting flange fixed to the end wall of the cylinder to surround and define the central aperture therein, a bearing plate permanently secured to the inner face of said end wall in opposition to said flange, said plate being pierced by a central opening in registration with the aperture in the end wall and a plurality of air passages radially disposed relative to said opening

ing, each air passage communicating at its opposed ends with the space defined by said flange and the cylinder, a compressor mounted for reciprocation in the open end of said cylinder comprising a body, normally positioned with the major part thereof projecting from the open end of the cylinder and provided with an end wall always located within the cylinder, a packing member resting flush against the end wall with its edge projecting beyond the limits thereof for sealing contact with the inner surface of the cylinder, and a clamping plate overlying the packing member and securing it in its operative position, said wall, packing member and clamping plate in association constituting the piston of the compressor, a piston rod affixed centrally to said piston to extend through the central openings of the bearing plate and end wall of the cylinder, a compression spring interposed between the end wall of the cylinder and the piston of the compressor tending to move the latter in a direction outwardly of the cylinder to its normal position, a tube having its outer end portion flared, fixed within and projecting outwardly from the space defined by the flange on the end wall of the cylinder, said tube having several openings in its wall adjoining the edge of said flange each opening being defined by relatively narrow connectors interposed between that part of the tube situated within said flange and the opposed edge of the tube, a permanent closure sealing the extremity of the flared end portion of the tube, a disc mounted in the tube adjacent the openings therein with its periphery spaced from the inner surface of the tube, said disc being provided with a central opening in axial alignment with the openings in the end wall of the cylinder and in the bearing plate for the reception and passage of the piston rod of the compressor, and an enlargement at the extremity of the piston rod externally of the disc to limit the movement of said rod and of the attached compressor outwardly of the open end of the cylinder under the influence of the aforesaid spring, by contact thereby with the outer face of said disc.

5. The combination with a cylinder having one of its ends open and its opposite end closed by a centrally apertured end wall, of an outwardly projecting flange fixed to the end wall of the cylinder to surround and define the central aperture therein, a bearing plate permanently secured to the inner face of said end wall in opposition to said flange, said plate being pierced by a central opening in registration with the aperture in the end wall and a plurality of air passages radially disposed relative to said opening, each air passage communicating at its opposed ends with the space defined by said flange and the cylinder, a compressor mounted for reciprocation in the open end of said cylinder comprising a body, normally positioned with the major part thereof projecting from the open end of the cylinder and provided with an end wall always located within the cylinder, a packing member resting flush against the end wall with its edge projecting beyond the limits thereof for sealing contact with the inner surface of the cylinder, and a clamping plate overlying the packing member and securing it in its operative position, said wall, packing member and clamping plate in association constituting the piston of the compressor, a piston rod affixed centrally to said piston to extend through the central openings of the bearing plate and end wall of the cylinder,

11

a compression spring interposed between the end wall of the cylinder and the piston of the compressor tending to move the latter in a direction outwardly of the cylinder to its normal position, a tube having its outer end portion flared, fixed within and projecting outwardly from the space defined by the flange on the end wall of the cylinder, said tube having several openings in its wall adjoining the edge of said flange each opening being defined by relatively narrow connectors interposed between that part of the tube situated within said flange and the opposed edge of the tube, a permanent closure sealing the extremity of the flared end portion of the tube, a disc mounted in the tube adjacent the openings therein with its periphery spaced from the inner surface of the tube, said disc being provided with a central opening in axial alignment with the openings in the end wall of the cylinder and in the bearing plate for the reception and passage of the piston rod of the compressor, a washer having a diameter greater than the diameter of the piston rod positioned concentrically to the extremity of said rod, and a screw piercing said washer and threaded into the extremity of the piston rod to secure said washer in its operative position whereby it contacts the outer surface of the disc aforesaid to arrest the movement of the compressor outwardly of the cylinder.

6. The combination with a hollow cylinder having one of its ends open and a centrally apertured wall at its opposite end, of an outwardly projecting flange fixed to the outer face of the wall to surround the central aperture therein, a bearing plate permanently secured to the inner face of said wall having a central aperture concentric to the aperture of the end wall and a plurality of air passages disposed about said aperture, each air passage at its opposed ends communicating respectively with the space defined by said flange and with said cylinder, a compressor mounted for reciprocation in the open end of the cylinder embodying a piston in sealed contact with the inner surface of the cylinder, a piston rod affixed centrally to the piston of the compressor and extending through the central aperture of the bearing plate, a compression spring interposed between the end wall of the cylinder and the compressor to normally move and position the latter in a direction outwardly of the cylinder, a tube fixed to and projecting outwardly from the flange on the end wall of the cylinder having its outer end portion flared and its wall adjoining the cylinder pierced by a pair of parallel, spaced, elongated openings, a permanent closure sealing the extremity of the flared end portion of the tube, a hollow rod reciprocatingly encircling said piston rod and projecting through the central aperture of the bearing plate, a sleeve mounted for reciprocation within the end of the tube associated with the flange as aforesaid having an elongated opening in its wall adapted to register with one or the other of the elongated openings in the tube, a disc secured to the outer extremity of said hollow rod with its periphery spaced from and secured to the wall of the sleeve, an enlargement on the extremity of the piston rod arranged to contact the outer surface of the disc to limit the movement of the compressor and piston rod outwardly of the open end of the cylinder, a secondary spring surrounding the piston rod adjacent the piston of the compressor and arranged to contact the inner end of the hollow rod after a partial movement of the compressor inwardly of the cylinder to move the hollow rod and the piston rod in

15 unison to register the opening in the sleeve with one of the openings in the tube while the body of the sleeve closes the other of said tube openings, and stop means within the tube to arrest the movement of the sleeve by the compressor.

7. The combination with a reciprocable compressor having an outlet opening for the expulsion of air under pressure, of a resonating tube open at one end and closed at the other, arranged with its open end in association with said outlet opening, said tube being provided with a pair of parallel spaced circumferential openings in its wall adjacent the open end thereof, and means actuated by the compressor to alternately open and close said openings in the wall of the tube.

8. The combination with a compressor having an outlet opening for the expulsion of air under pressure, of a resonating tube closed at one of its ends and open at the opposite end, arranged with its open end in association with said outlet opening, said tube having in its wall a pair of parallel circumferential openings spaced one from the other longitudinally of the tube, a hollow sleeve mounted for reciproction within the open end portion of the tube having a single circumferential opening in its wall medially of its ends for registration with one or the other of the aforesaid openings in the tube whereupon the body of the sleeve closes the other of said openings, a restriction within said sleeve in substantial alignment with one side of the sleeve opening, and means whereby the sleeve may be reciprocated in the tube to register its opening with one or the other of the tube openings and simultaneously close the tube opening out of registration with the sleeve opening.

9. The combination with a compressor having an outlet opening for the expulsion of air under pressure, of a resonating tube closed at one of its ends and open at the opposite end, arranged with its open end in association with said outlet opening, said tube having in its wall a pair of parallel circumferential openings spaced one from the other longitudinally of the tube, a hollow sleeve mounted for reciprocation within the open end portion of the tube having a single circumferential opening in its wall medially of its ends for registration with one or the other of the aforesaid openings in the tube whereupon the body of the sleeve closes the other of said openings, a restriction within said sleeve in substantial alignment with one side of the sleeve opening, and means actuated by the compressor for reciprocating the sleeve within the tube to alternately register the opening in the sleeve with one or the other of the tube openings and simultaneously close the other of said openings with an imperforate part of the sleeve.

10. The combination with a reciprocable compressor having an outlet opening for the expulsion of air under pressure, of a resonating tube closed at one of its ends and open at its opposite end, arranged with its open end associated with the outlet opening of the compressor, said tube having, adjacent the compressor, a pair of parallel circumferential openings spaced one from the other longitudinally of the tube, a sleeve mounted for reciprocation in the tube having a single circumferential opening in its wall medially of its ends for registration with one or the other of the tube openings whereupon the body of the sleeve closes the other of said openings, a restriction within said sleeve in substantial alignment with the inner side of the opening in the sleeve, and means whereby said sleeve may be reciprocated

12

within the tube by said compressor to maintain the sleeve opening in registration with one of the tube openings during part of a stroke of the compressor and in registration with the other of the tube openings during the remainder of the same compressor stroke.

11. The combination with a reciprocable compressor having an outlet opening for the expulsion of air under pressure, of a resonating tube associated with said outlet opening having parallel circumferential openings in its wall, a hollow sleeve mounted for reciprocation within the tube provided with a single medial circumferential opening therein, a restriction within the sleeve adjacent one side of the opening therein, and means whereby the actuation of the compressor in either direction will successively register said sleeve opening with the tube openings simultaneously closing the opening out of registration with the sleeve opening.

12. The combination with a reciprocable compressor having an outlet opening, of a resonating tube associated with said opening having parallel circumferential openings in its wall adjacent said compressor, a hollow sleeve having a single medial circumferential wall opening mounted for reciprocation within the tube, a restriction within the sleeve adjacent one side of the opening therein, and means whereby the actuation of the compressor in one direction will successively register the sleeve opening with openings in the tube whereby air expelled by the compressor will pass said restriction and be discharged first through one of the tube openings and then the other.

13. The combination with a cylinder having an outlet opening, of a piston mounted for reciprocation in said cylinder, a piston rod projecting concentrically from said piston, a hollow rod mounted for independent reciprocation upon said piston rod, a resonating tube closed at one end and open at the opposite end arranged with its open end in association with the outlet opening of the cylinder, said tube having a pair of spaced openings in its wall, a sleeve mounted for reciprocation within the tube having a single opening in its wall medially of its length, a disc affixed to the extremity of said hollow rod and spaced from and secured to the sleeve at one side of the opening therein, a spring associated with the piston rod to normally move it in a direction away from the outlet opening and position the sleeve with its aforesaid opening in registration with one of the openings in the tube, whereupon the

reciprocation of the piston and piston rod against the action of the spring and toward the outlet opening will be independent of the sleeve during the first part of this movement, and means to move the sleeve in unison with the piston during the last part of the movement of the piston toward the outlet opening to a position where the opening in the sleeve registers with the second opening in the tube wall and the sleeve closes the first said opening.

14. The combination with a cylinder having an outlet opening, of a resonating tube associated with said outlet opening, said tube having at least two openings in its wall spaced one from the other longitudinally of the tube, a hollow sleeve having a single opening medially of its length, mounted for limited reciprocation within the tube, a disc fixedly mounted within the sleeve adjacent one side of the sleeve opening and spaced peripherally from the inner surface of the sleeve, a piston mounted for reciprocation within the cylinder to expel air under pressure through the outlet opening and sleeve as it moves in one direction, a piston rod secured to said piston to reciprocate through said outlet opening and in the adjacent end portion of the tube, a hollow rod encircling said piston rod and at its end centrally secured to the disc aforesaid, and means whereby the initial movement of the piston and rod in the direction to expel air under pressure through the outlet opening will be independent of and relative to said hollow rod and sleeve whereupon the piston and piston rod become coupled to the hollow rod and sleeve for operation in unison therewith during the remainder of the movement to expel air under pressure as aforesaid.

LAWRENCE ABBONDANDOLO.
